Primary Examiner—Ruth McInroy
Attorney, Agent, or Firm—A. Burgess Lowe; Richardson B. Farley[57] **CLAIM**

The ornamental design for a medial front portion of a suction nozzle, as shown and described.

DESCRIPTION

FIG. 1 is a top plan view of a medial front portion of a suction nozzle showing our new design;
 FIG. 2 is a front elevational view thereof;
 FIG. 3 is an enlarged top plan view thereof;
 FIG. 4 is a cross-sectional view thereof taken along lines 4—4 in FIG. 3;
 FIG. 5 is a cross-sectional view thereof taken along lines 5—5 in FIG. 3;
 FIG. 6 is a cross-sectional view thereof taken along lines 6—6 in FIG. 3;
 FIG. 7 is a cross-sectional view thereof taken along lines 7—7 in FIG. 3; and,
 FIG. 8 is a cross-sectional view thereof taken along lines 8—8 in FIG. 3.

The portions shown in broken lines in FIGS. 1 through 8 are shown for illustrative purposes only and form no part of the claimed invention.
